CLAIM

The ornamental design for a crimping hand tool, as shown and described.

DESCRIPTION

FIG. 1 is a perspective view of a crimping hand tool showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is another perspective view showing a crimping state thereof;

FIG. 10 is another perspective view showing the crimping state thereof;

FIG. 11 is another front view showing the crimping state thereof; and,

FIG. 12 is another rear view showing the crimping state thereof.

The broken lines illustrate portions of the crimping hand tool that form no part of the claimed design. The dot-dash broken lines define the bounds of the claimed design and form no part thereof.

1 Claim, 10 Drawing Sheets
